J.F. Brown,

Washing Machine,

No 15,684,

Patented Sept. 9, 1856.

Fig 1.

Fig 2.

UNITED STATES PATENT OFFICE.

I. F. BROWN, OF COLUMBUS, GEORGIA.

WASHING-MACHINE.

Specification of Letters Patent No. 15,684, dated September 9, 1856.

To all whom it may concern:

Be it known that I, ISRAEL F. BROWN, of Columbus, in the county of Muscogee and State of Georgia, have invented a new and 5 Improved Clothes-Washing Machine; and I do hereby declare that the following is a full, clear, and exact description of the same, reference being had to the annexed drawings, making a part of this specification, in 10 which—

Figure 1, is a transverse vertical section of my improvement. Fig. 2, is a longitudinal vertical section of ditto.

Similar letters of reference indicate 15 corresponding parts in the two figures.

My invention consists in the employment 20 or use of a rotating slatted cylinder provided with a diagonal or oblique corrugated board at each end, as will be hereinafter fully shown and described.

To enable those skilled in the art to fully understand and construct my invention, I will proceed to describe it.

A, represents a box of a suitable size in 25 which soap and water is placed; and B, represents a cylinder the axis of which works in proper bearings on the box, the cylinder being immersed a suitable depth in the water.

30 The cylinder is formed of two solid end pieces (a), (a), connected near their edges by cylindrical bars (b), which are placed at suitable distances apart.

Within the cylinder B, and at each end, a

diagonal or oblique corrugated board (a), 35 is placed, the two boards being parallel with each other as shown in Fig. 2.

The cylinder B, is provided with a door, or a portion of it may be bisected and connected by hinges so that it can be raised to 40 allow the clothes to be placed within the cylinder.

The clothes C, are placed in a sack constructed of netting, a weight or ball (c), 45 being placed within the clothes.

As the cylinder B, is rotated the clothes C, are thrown back and forth longitudinally with the cylinder as they rotate, and are consequently subjected to the necessary friction to cleanse them thoroughly from dirt and 50 at the same time without injury from undue friction or rubbing. The whole of the clothes are subjected to the necessary friction, because they are continually changing 55 their position.

Having thus described my invention, what I claim as new and desire to secure by Letters Patent, is,

The slatted cylinder B, constructed as 60 shown and having a diagonal or oblique corrugated board (a'), at each end, the cylinder being partially immersed within the box A; substantially as shown and described for the purpose specified.

ISRAEL F. BROWN.
